UNITED STATES PATENT OFFICE.

HARMON E. LINDEBLADH, OF BROOKLINE, MASSACHUSETTS.

SHEET-CONTROLLING APPARATUS.

Application filed January 13, 1921. Serial No. 436,970.

To all whom it may concern:

Be it known that I, HARMON E. LINDEBLADH, a citizen of the United States, residing at Brookline, in the county of Norfolk and State of Massachusetts, have invented a new and useful Sheet-Controlling Apparatus, of which the following is a specification.

In the supplying of sheets of such material as paper to machines in which they are to be operated upon, for example ruling machines, when this feeding is effected by hand, it is customary to overlap the succeeding sheets, the rear extremity of each being beneath that following it. The gates of ruling machines are arranged to rest normally upon the conveyors by which the sheets are advanced, contacting with the forward edge of each sheet to temporarily stop its progress, and then quickly lifting and returning to normal to release the sheet in a definite time-relation to the ruling mechanism. When the sheets are overlapped, as just indicated, their control may be accomplished accurately and efficiently. The gate rises to release the sheet, and then falls upon its surface, the released sheet being drawn under it by the conveyor, while the next sheet resting upon that just mentioned is caught promptly and with certainty by the gate for like release. If, instead of being thus overlapped, the forward edge of this second sheet is just at the rear of the sheet preceding, it may in its travel with the conveyor get caught beneath the leading sheet. In that case it slides beneath the lowered gate without being arrested, the timing with respect to the ruling mechanism is lost, and the sheet spoiled. If the distance between adjacent sheets is increased somewhat to avoid this result, the gate may rise again before the forward end of the sheet reaches it, and then fall upon the sheet-surface, destroying the timing, as in the previous instance. A still further increase of the space between the sheets may avoid their misruling, but at the sacrifice of considerable time. Automatic feeders are so organized

that they cannot overlap the sheets, and their rate of delivery is not uniform. Consequently, to avoid the waste of stock by incorrect ruling, the practice is to slow the feed, introducing a time-loss, which frequently decreases the efficiency of the ruling machine supplied by over twenty-five per cent. An object of the present invention is to provide means, combined particularly with such apparatus as ruling machines, to automatically overlap the sheets before their delivery to the machine supplied, said means being capable of operating upon sheets of different lengths.

To prepare sheets fed for delivery in the correct transverse relation to a mechanism which is to act upon them, there is commonly placed at one side of the conveyor advancing them to such mechanism, a gage-wall, against which the sheets are forced during their travel by light spring-fingers, known as "flies," contacting with the opposite edges of the sheets from the gage. This arrangement introduces serious difficulties in feeding. Sheets are not cut accurately as to dimensions, and, of course, to be effective in pressing the sheets against the gage, the flies must bear upon all with some pressure. This pressure may deform the edges of the sheets, particularly the wider, and their forward corners sometimes catch against the first fly, twisting the sheet upon the conveyor, and causing it to be badly ruled. If a lighter pressure is sought, narrow sheets will not be held to the gage, and the ruled lines will be misplaced. As a further object of the invention, I furnish means which will, under all usual conditions, assist, rather than interfere with the feed of the sheets during their gaging, and which will functionate properly with sheets differing considerably in width. This gaging means is of peculiar utility in connection with the overlapping means previously discussed, in effectively positioning sheets which may have been displaced in the overlapping process.

In the accompanying drawing, illustrating a particular embodiment of my invention,

Figure 1 is a perspective view of my improved apparatus, parts being broken away; Fig. 2 is a longitudinal section therethrough, showing a portion of the receiving end of a ruling machine; and Fig. 3 is a detail in top plan view of the rotatable gaging device 10 and its driving mechanism.

Like reference characters designate similar parts throughout the several views.

In oppositely spaced, suitably supported side-frames 10, 10 are journaled, near the ends, rolls 11 and 12 over which operates a conveyor, preferably furnished by spaced tapes 13. To one of these rolls, as 11, power is applied in any convenient manner to advance the upper runs of the tapes in the direction of the arrow in Fig. 2. This conveyor may receive at one end sheets delivered by any feeder, as that disclosed in my Patent No. 1,258,028, dated March 5, 1918. This machine is not here illustrated. At the opposite end the conveyor discharges sheets upon the cloth or conveyor 14 of a ruling machine, of which, in addition to the cloth, there are shown only the receiving rolls 15, 15 and the gate 16 with its operating cam 17. The elements appearing correspond to those of the machine of Patent No. 1,242,823, issued in my name on October 9, 1917. Between the rolls 11 and 12, sliding in ways 18 at the inner sides of the frames 10, are opposite bearing blocks 19, 19, and in these blocks are journaled transversely extending rolls or guide members 20 and 21 located upon opposite sides of the conveyor. These rolls are displaced both longitudinally of the frame and vertically, the roll 21 being below and in advance of its companion. As a result of this, the upper run of the conveyor, in passing over the roll 20, is directed downwardly from its approximately horizontal line of travel into a lower plane in proximity to the under run of the conveyor, and then passes beneath the roll 21, and again forwardly in a generally horizontal plane, which may be parallel to that of the portion at the rear of the roll 20.

Mounted to turn in the side-frames 10, at opposite sides of the bearing blocks 19, are shafts 22, on each of which is mounted a pair of pulleys 23, 23, preferably lying within the ways 18. Over the longitudinally aligned pulleys of these pairs operate belts 24, 24, the upper ends of which are secured at 25 to the tops of the bearing blocks. The under runs of the belts 24 are shown as passing through recesses 26 in the lower side of the blocks. Upon one of the shafts 22 is fixed a crank 28 to enable the operator to turn the shaft conveniently, and by the contact of its pulleys with the belts 24, shift the bearing blocks simultaneously in one

direction or the other along the frame. As the rolls 20, 21 travel together, this will be accomplished without disturbing the conveyor, or varying its tension, it merely changing the relative lengths of the two differently elevated portions of the upper run of the conveyor 13. To avoid accidental displacement of the rolls after they have been thus set, a screw 29 may be threaded through one of the side-frames for contact 75 at its inner end with the adjacent face of a pulley 23.

Referring particularly to Fig. 2 of the drawing, it will be seen that a sheet, as that designated by the letter A, is advanced so along the conveyor-tapes 13 and is stopped by the gate 16 of the ruling machine, partly upon the lower portion of the conveyor 13 and partly upon the conveyor 14. It may there be held while the succeeding sheet B, 85 traveling upon the upper portion of the conveyor 13, is projected over it. Then, as the gate rises and permits the advance of the sheet upon the conveyor 14, as is indicated at C, the two sheets A and B will travel together at the same speed, but with the overlap which has been created during the period of rest of the forward sheet. When sheets of another length are to be fed, the position of the rolls 20, 21 may be suitably altered by loosening the screw 29 and turning the crank 28 in one direction or the other to change the space between the rolls 20, 21 and the gate. By this adjustment the overlapping of sheets of any dimension may 100 readily be effected.

At one side and extending along the lower portion of the upper run of the conveyor 13, is a gage member 30, presenting an inner vertical wall for contact with the edges 105 of the sheets fed. This gage is preferably adjustable toward and from the conveyor, being mounted upon a bracket 31 movably secured to the side-frame, a variation in its position correspondingly changing the presentation of the sheets to the ruling mechanism. At the opposite side of the path of the sheets from the gage 30 is a rotatable contact device, including a disk 32 turning about its vertical axis on a support 33 arranged to slide on a cross-bar 34 extending between the frame-walls. The slide may be fixed in position upon the bar at any desired point by a set-screw 35, which I have illustrated as threaded through the under side 120 of the support, and contacting at its inner end with the adjacent surface of the bar. Rising from the upper face of the disk, above the tapes, are fingers or projections 36, which may be flexible if desired and 125 which are eccentrically placed. Of these fingers, four are shown, symmetrically spaced about the periphery of the disk. This latter element is grooved to receive a belt 37, which passes from it outwardly and 130

downwardly over a pair of pulleys 38, 38 journaled in a bearing upon the upper surface of the bar 34, then beneath the support, upwardly over the pulleys 39, 39 rotatably mounted near the opposite end of the bar, and finally horizontally about a pulley 40, turning about a vertical axis upon the support 33 adjacent to the disk 32. Fixed to the shaft of the pulleys 39 is a pulley 41, driven by a belt from some convenient source of power, so that the disk 32 will rotate in the direction of the arrow in Fig. 3.

In using this gaging device, the gage 30 having been correctly placed, the set-screw 35 is loosened, and the disk 32 is so set with respect to the gage, that when a finger 36 is nearest it, the space between the two elements will be less than the narrowest sheet. The distance to the fingers on each side of this may be greater than any of the sheets operated on. This adjustment, it is to be observed, takes place without interference with the action of the belt 37, the amount which this is shortened at one side in the movement of the support being compensated for by the simultaneous lengthening of the portion at the other side. The spaced tapes furnishing the conveyor allow the contact device to be positioned at any chosen point, the fingers passing between them. Now as each sheet reaches the rotating member, the revolving fingers successively tap its adjacent edge, with a slight yield if they are flexible, and in doing so, move with it, so that instead of their resisting its advance, this is facilitated. This tapping action gradually, and without deforming the edge of the sheet, moves the opposite side into contact with the gage 30, truing said sheet for delivery to the ruling mechanism.

I claim:

1. The combination with a plurality of means for successively advancing sheets, each of said means causing the advance of the sheets at substantially the same speed, of means associated with one of the advancing means for overlapping the sheets, and means associated with the succeeding advancing means for stopping the advance of the sheets.

2. The combination with an endless sheet-conveyor having upper and lower runs, of adjacent rolls contacting respectively with the inner and outer surfaces of the upper run to furnish differently elevated portions thereof, a conveyor-belt receiving sheets from the lower portion of the upper run of the conveyor, and a movable gate normally contacting with said belt and arranged for engagement with sheets resting upon both the conveyor and the belt.

3. In combination, an overlapping apparatus having advancing means for the overlapped sheets, and a ruling machine pro-

vided with a belt arranged to receive the sheets from the overlapping apparatus and advance them at substantially the same speed thereas and with a gate arranged to engage a sheet which is under the influence of both the advancing means of the overlapping apparatus and of the ruling machine belt.

4. The combination with a plurality of means for successively advancing sheets, each of said means causing the advance of the sheets at substantially the same speed, of means associated with one of the advancing means for overlapping the sheets, means associated with the succeeding advancing means for stopping the advance of the sheets, and means arranged to vary the distance between the overlapping means and stopping means in accordance with the dimensions of the sheets to be overlapped.

5. In a sheet-controlling apparatus, a frame, opposite bearings movable along the frame, rolls journaled in the bearings, an endless conveyor arranged to travel along the frame and passing between the rolls, pulleys mounted upon the frame at opposite sides of the bearings, and belts passing over the pulleys, each belt being connected to a bearing.

6. In a sheet-controlling apparatus, a frame, opposite bearings movable along the frame, rolls journaled in the bearings, an endless conveyor arranged to travel along the frame and passing between the rolls, shafts journaled in the frame at opposite sides of the bearings, a pair of pulleys fixed on each shaft in alignment with the bearings, and a belt passing over the pair of pulleys at each side of the frame and having both ends secured to a corresponding bearing.

7. In a sheet-controlling apparatus, means for advancing the sheets, a gage co-operating with one edge of the advancing sheets, a contact device for co-operation with the opposite edge of the sheets, and means for moving the contact portion of said device in the direction of advance of the sheets.

8. In a sheet-controlling apparatus, means for advancing the sheets, a gage co-operating with one edge of the advancing sheets, a contact device for co-operation with the opposite edge of the sheets, and means for moving said device in contact with the sheets and in the direction of their advance.

9. In a sheet-controlling apparatus, means for advancing the sheets, a gage co-operating with one edge of the advancing sheets, a rotatable contact device for co-operation with the opposite edge of the sheets, and means for rotating said device.

10. In a sheet-controlling apparatus, means for advancing the sheets, a gage co-operating with one edge of the advancing sheets, a rotatable, yieldable contact device for co-operation with the opposite edge of the sheets, and means for rotating said device.

11. In a sheet-controlling apparatus, means

- for advancing the sheets, a plurality of contact members arranged for co-operation with one edge of the sheets, and means for revolving the members into successive contact with the sheets.
12. In a sheet-controlling apparatus, means for advancing the sheets, a gage co-operating with one edge of the advancing sheets, and a plurality of revoluble members arranged to contact with the opposite edge of the sheets.
13. In a sheet-controlling apparatus, a sheet-conveyor, and a movable member having an eccentrically placed projection extending above the sheet-carrying surface of the conveyor and arranged to contact with an edge of each sheet.
14. In a sheet-controlling apparatus, a sheet-conveyor, and a movable member having an eccentrically placed flexible projection extending above the sheet-carrying surface of the conveyor and arranged to contact with an edge of each sheet.
15. In a sheet-controlling apparatus, a sheet-conveyor, and a movable member having a plurality of projections extending above the sheet-carrying surface of the conveyor and arranged for successive contact with an edge of each sheet.
16. In a sheet-controlling apparatus, a sheet-conveyor, and a movable member having a plurality of projections extending above the sheet-carrying surface of the conveyor and arranged for successive contact with an edge of each sheet opposite that adjacent to the gage.
17. In a sheet-controlling apparatus, separated sheet-conveying members, and a revoluble member projecting between the conveying members for contact with an edge of the sheets.
18. In a sheet-controlling apparatus, means for advancing the sheets, a gage co-operating with one edge of the advancing sheets, a rotatable contact device for co-operation with the opposite edge of the sheets, and means arranged to vary the position of the contact device transversely of the conveyor.
19. In a sheet-controlling apparatus, a sheet-conveyor, a movable member having an eccentrically placed projection extending above the sheet-carrying surface of the conveyor and arranged to contact with an edge of each sheet, and means arranged to vary the position of the member transversely of the conveyor.
20. In a sheet-controlling apparatus, means for advancing the sheets, a gage co-operating with one edge of the advancing sheets, a contact device for co-operation with the opposite edge of the sheets, means arranged to vary the position of the contact device transversely of the sheets, and means for moving said device, the moving means being constructed and arranged to maintain a uniform effect for all positions of the device.
21. In a sheet-controlling apparatus, a sheet-conveyor, a support movable transversely of the conveyor, and a movable contact device mounted upon the support. 70
22. In a sheet-controlling apparatus, a sheet-conveyor, a support movable transversely of the conveyor, a rotatable contact device mounted upon the support, and means arranged to fix the support in different positions. 75
23. In a sheet-controlling apparatus, a sheet-conveyor, a support movable transversely of the conveyor, a movable contact device mounted upon the support, a driving belt for the contact device, and pulleys guiding the belt and being mounted at each side of the support and on said support. 80
24. In a sheet-controlling apparatus, a sheet-conveyor, a support movable transversely of the conveyor, a movable contact device mounted upon the support, a pair of pulleys situated at each side of the support, a pulley mounted on said support, and a driving belt co-operating with the device and traveling over the pulleys. 85
25. The combination with an endless sheet-conveyor, of means associated with the conveyor for overlapping the sheets thereon, a conveyor-belt receiving the sheets from said sheet-conveyor, and a movable gate contacting with said belt and arranged for engagement with the overlapped sheets resting upon both the conveyor and the belt. 95
26. A sheet-controlling apparatus comprising means for advancing the sheets, means associated with said advancing means for overlapping the sheets, a gage co-operating with one edge of an overlapped sheet, and a movable contact device co-operating with the opposite edge. 105
27. A sheet-controlling apparatus comprising means for advancing the sheets, said advancing means having sheet-carrying portions lying in different planes and being arranged to project a sheet from the upper portion upon a sheet resting upon the lower portion, and a gage and rotatable contact device co-operating with the sheets upon the lower portion. 110
28. A sheet-controlling apparatus comprising an endless conveyor having upper and lower runs, means for changing the direction of advance of the upper run downwardly and then forwardly, and gaging means co-operating with the sheets upon the forwardly advancing portion of said upper run. 120
29. A sheet-controlling apparatus comprising an endless conveyor having upper and lower runs, means for changing the direction of advance of the upper run downwardly and then forwardly, means for tem- 130

porarily stopping the advance of the sheets upon the forward portion of said upper run, and gaging means co-operating with the sheets between the direction-changing means and the stopping means.

30. A sheet-controlling apparatus comprising an endless conveyor having upper and lower runs, adjacent rolls contacting respectively with the inner and outer surfaces of the upper run to furnish differently

elevated portions thereof, a movable gate acting upon the sheets on the lower portion, and a gage and rotatable contact device co-operating with opposite edges of the sheets between the rolls and gate.

15

Signed at Boston, in the county of Suffolk and State of Massachusetts, this 11th day of January 1921.

HARMON E. LINDBLADH.
